UNITED STATES PATENT OFFICE.

ERNEST PACE, OF WIRT, OKLAHOMA.

SUCKER-ROD REMOVER.

Application filed December 28, 1922. Serial No. 609,450.

To all whom it may concern:

Be it known that I, ERNEST PACE, a citizen of the United States, residing at Wirt, in the county of Carter and State of Oklahoma, have invented certain new and useful Improvements in Sucker-Rod Removers; and I do hereby declare the following to be a full, clear, and exact description of the invention, such as will enable others skilled in the art to which it appertains to make and use the same.

The invention has for its primary object the provision of a tool whereby a broken sucker rod may be removed from a well whether the break is at a joint or intermediate the joints, the tool embodying a latch to positively engage the shoulder when the sucker rod breaks at a joint and embodying a friction grip to engage the sucker rod when the break is at a point between the joints.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a sectional view of the tool,

Figure 2 is a detail sectional view showing the latch which is adapted to engage a shoulder,

Figure 3 is a detail section of the friction grip,

Figure 4 is a horizontal section on the line 4-4 of Figure 3, and

Figure 5 is a detail perspective view of the friction grip, the parts being separated.

Corresponding and like parts are referred to in the following description and designated in the several views of the drawings by like reference characters.

The tool embodies a casing 1 which may be a length of pipe of required size. The casing 1 contains the elements for engaging the sucker rod or other analogous part to be removed from a well. An opening 2 is formed in a side of the casing 1 and a latch 3 is pivoted at one end to a side of the casing and is adapted to swing across the opening 2 and have its outer marginal portion engage and rest upon the part of the casing

bordering upon the lower end of the opening 2. The outer marginal portion of the latch 3 is rabbeted, as indicated at 4, to receive the part of the casing upon which it rests, so that the shoulder formed by the rabbet engages the inner wall of the casing and prevents outward or lateral displacement of the latch when under stress, as when lifting a sucker rod or like part. It is observed that the latch 3 is located wholly at one side of the casing 1 and extends there-in sufficiently far to engage the shoulder of a sucker rod when the break is at the joint.

The friction grip for engaging the sucker rod when the break is intermediate the joint, comprises a head 5, a gripping element or jaw 6 in line with a side of the head 5 and extending longitudinally thereof from one end. The gripping element or jaw 6 tapers throughout its length, being of a maximum thickness at its free end. The inner face of the gripping element or jaw 6 is formed in its length with a half-round groove 7 and the extremity of the jaw is beveled. A complementary jaw or gripping element 8 is of uniform thickness throughout and is provided at its inner end with a lateral extension 9. The inner face of the jaw 8 is provided with a half-round groove 10 which flares at the outer end of the jaw. A wedge 11 is disposed between the fixed jaw 6 and the movable jaw 8 and its outer side is formed with a half-round projection 12 to match the half-round groove 7 of the jaw 6 and its inner face is formed with a half-round groove 13 to match the half-round groove 10 of the loose or movable jaw 8. The outer edge of the wedge 11 is beveled outwardly from the groove 13 and with the beveled ends of the jaws 6 and 8 direct the end of a sucker rod to be recovered into the opening formed by the matching half-round grooves 10 and 12. These grooves are corrugated or toothed to insure a firm grip upon the sucker rod or other implement to be recovered from a well.

While it is preferred to embody both the latch 3 and the friction grip in a single tool, thereby adapting the same for recovering shouldered or plain rods, nevertheless in practice the tool may contain either the latch 3 or the friction grip, but not both, whereby it is adapted for shouldered rods only or for plain rods.

The head 5 is secured in the casing 1 by means of a pin 14 or in any preferred way.

Downward displacement of the wedge 11 and jaw 8 is prevented by the wedge form of the jaw 6 as shown most clearly in Figure 1. An expansible helical spring 15 is interposed between the head 5 and the upper end of the jaw 8 to insure holding the parts 8 and 11 at the limit of their downward movement. The jaw 8 and wedge 11 have a limited vertical movement to admit of their separation so that a rod or tool may be received between them and gripped by a wedging action.

What is claimed is:

1. In a tool of the character specified, a friction grip comprising a head, a jaw at one side of the head and in line therewith and increasing in thickness towards its outer end, a complemental movable jaw, and an intermediate wedge between the two jaws.
2. In a tool of the character specified, a friction grip comprising a head, a jaw at one side of the head and in line therewith and increasing in thickness towards its outer end, a complemental movable jaw, and an intermediate wedge between the two jaws, the fixed jaw having its inner face longitudi-

nally grooved and the wedge having a corresponding projection upon its outer side, and the opposing faces of the wedge and movable jaw being correspondingly grooved.

3. A tool of the character specified including a friction grip having a head, a jaw at one side of the head and in line therewith and increasing in thickness toward its outer end, a complemental jaw, an intermediate wedge between the two jaws, the fixed jaw having its inner face longitudinally grooved and the wedge having a corresponding projection upon its outer side, the opposing faces of the wedge and movable jaw being correspondingly grooved, and a coil spring interposed between the head and the upper end of the movable jaw to hold the jaw and wedge at the limit of their downward movement.

In testimony whereof I affix my signature in presence of two witnesses.

ERNEST PACE.
